CLAIM

The ornamental design for a jewelry clasp, as shown and described.

DESCRIPTION

FIG. 1 is a top perspective view of a jewelry clasp showing my new design;

FIG. 2 is a bottom perspective view thereof;

FIG. 3 is a top plan view thereof;

FIG. 4 is a bottom plan view thereof;

FIG. 5 is a front view thereof;

FIG. 6 is a rear view thereof;

FIG. 7 is a right side view thereof;

FIG. 8 is a left side view thereof;

FIG. 9 is a top perspective view thereof, shown with bracelet links in broken lines as environment;

FIG. 10 is a top plan view thereof in an unassembled state; and,

FIG. 11 is a bottom plan view thereof in an unassembled state.

The broken lines shown on the jewelry clasp are included for the purpose of illustrating portions of the jewelry clasp that form no part of the claimed design, and in FIG. 9 the bracelet links shown in broken lines illustrate environmental structure that forms no part of the claimed design.

1 Claim, 9 Drawing Sheets
